UNITED STATES PATENT OFFICE.

CHARLES N. CORYELL, OF NEW YORK, N. Y.

ARTICLE HOLDER.

Application filed December 23, 1926. Serial No. 156,618.

This invention relates to a functionally and structurally improved article holder.

It is an object of the invention to provide a device of this character which may be utilized for the housing and exposing of articles and plastic substances, such as, for example, combs, shaving brushes, lip-sticks and the like, and the parts of which device will be relatively few in number, individually simple in construction, and readily assembled to provide an apparatus normally housing an article to thoroughly protect the same, and the parts of which may be operated with facility; the device being capable of use over a relatively long period of time with freedom from mechanical difficulty.

It is a further object of the invention to provide a device of the character stated which, when utilized as a holder for a plastic stick, will operate in such a manner that the fingers of the user will not come into contact with the stick during such operation, and in which, regardless of the article housed, the mechanism will not contact with such article to the detriment of both.

The invention accordingly comprises the features of construction, combination of elements and arrangement of parts which will be exemplified in the construction herein-after set forth, and the scope of the application of which will be indicated in the claims.

For a fuller understanding of the nature and objects of the invention reference should be had to the following detailed description taken in connection with the accompanying drawings, in which:

Figure 1 is a sectional side view of one form of holder embodying the improved construction of the present invention and showing the parts thereof in their normal position;

Fig. 2 is a similar view, but showing the cover moved from its receptacle-closing position;

Fig. 3 is a view similar to Figs. 1 and 2, showing the article-mounting member in elevation and projected;

Fig. 4 is an edge view of the holder as shown in Fig. 1; and

Fig. 5 is a side view thereof, and indicating in dotted lines the position which the parts may assume.

The numeral 10 indicates the receptacle portion of the holder, which, in the present instance, is in the form of an open-ended tube, oval in cross section. Mounted for

sliding movement within this receptacle is an article-mounting member including a cup-shaped body 11, conforming substantially to the inner face of the tube and of a size 60 slightly smaller than the same. The movements of this holder are confined to points within the tube by, for example, a portion 12 forming a part of the receptacle body and extending inwardly adjacent the lower end 65 of the same, and an inwardly-struck portion 13 at the upper end of the tube. The portions 12-13 extend inwardly to an extent sufficient to intersect the path of travel of the mounting member 11, and thus act as 70 stops preventing the projection of this member beyond the tube ends.

It will be observed that an article 14 (indicated in dotted lines) will have its side faces normally protected from outside contact by the side walls of the tube 10, and its lower end likewise will be protected by the base of the cup-shaped mounting member 11. Now, in order normally to protect the upper end of this article, a cover is provided, including a body 15 of an area and shape slightly in excess of the upper tube end, and this cover may be formed with downwardly-depending side flanges 16 to engage the side faces of the tube as the cover 80 is moved into position, thus guiding the cover during such movement. At its outer end the cover may be formed with a downwardly-extending projection 17, which, as the cover moves across the open-tube end, 85 rides over the upper edge of the receptacle at the indented portion 13 thereof and snaps into position, thus preventing an accidental retraction of the cover from its receptacle-closing station.

According to the present invention, it is intended that the cover shall serve as an actuating medium for the article-mounting member 11, and to this end, as well as preventing the loss of the cover, a strip 18 is provided having one of its ends rigidly secured to, or, as shown, forming an integral part of the cover body, this strip being of a length substantially equal to the length of the tube and having its lower end secured 100 to the cup-shaped member 11. Preferably, this latter connection is established by having the lower or inner end of the strip coiled around a pivot pin 19 fixedly secured to the cup member 11. At a point short of the 105 pivot the strip is bent to extend at right angles to its body, as at 20, and this inturned

portion is preferably arcuate and of a length sufficient to bridge the space between the pivot pin and the outer face of the tube, so that when the article 14 is in housed position the parts lie snugly adjacent each other, as shown in Figs. 1, 4 and 5. It will be apparent that in such position this strip portion, in cooperation with the lower edge of the tube adjacent which it extends, will serve 10 as a lock preventing a movement of the article-mounting member with respect to the tube. Such movement will be prevented even when the parts reach the position indicated by dotted lines in Fig. 5, but upon the strip 15 18 being swung from the position shown in full lines in the figures aforementioned through an arc of substantially 180°, the lock provided by the parts aforementioned will be released; and by pressure being applied 20 to the outer face of the cover 15, it will be obvious that a projection of the mounting member 11 will follow, in that this thrust will be transmitted to the mounting member by means of the strip 18. As a consequence, 25 the mounting member may be moved to the position shown in Fig. 3, at which its further projection will be prevented incident to the engagement of the mounting member with the inner face of the in-struck portion 30 13.

At this time it will be observed that, with a view to preventing a swinging of the cover and associated parts beyond a point at which the connecting member 18 extends substantially parallel to the path of travel of the mounting member, the base of the cup member 11 may be in-struck, as has been indicated at 21, this portion being disposed so that the heel of the arcuate portion 19 will 35 engage therewith when the connecting member 18 assumes a position substantially in line with the axis in the tube, as has most clearly been shown in Fig. 2.

When it is desired to retract the parts it is 40 obvious that this may be accomplished simply by pulling the cover downwardly until the mounting-member reaches a position adjacent the lower end of the tube, at which its further movement will be prevented incident 45 to engagement between the base of the cup 11 and the inturned portion 12. Thereupon the cover may be swung through the position indicated in dotted lines in Fig. 5, until it rides over the open end of the tube, and the projection 50 17 snaps over the far tube edge; it being noted, as aforeslated, that during this latter stage of movement the cover will be guided incident to the engagement of its flanges 16 with the outer tube faces.

Obviously, an article holder embodying the characteristics of the present invention will offer numerous advantages, among which are to be noted that the tube walls being 55 uninterrupted and the tube ends being normally closed, the entrance of foreign mat-

ter into the tube and into contact with the article will be virtually precluded. Furthermore, there will be no danger of the article being mutilated and distorted incident to contact with the moving parts of the holder, 70 and also no movement of the article from housed to exposed position may be effected until the fingers of the operator are at a point remote from the open tube end. It will follow in the latter connection that the 75 article will not contact with the operator's fingers, thus preventing a soiling of the latter and any distortion of the article end or body. The exposing and retraction thereof may be readily accomplished, and the parts 80 will remain in the position in which they are disposed without any danger of the holder becoming accidentally opened after the cover has once been moved to its tube-closing position. 85

Thus, among others, the objects specifically aforementioned are achieved, and since certain changes may be made in the above construction, and different embodiments of the invention could be made, without departing from the scope thereof, it is intended that all matter contained in the above description or shown in the accompanying drawings 90 shall be interpreted as illustrative and not in a limiting sense. 95

It is also to be understood that the following claims are intended to cover all of the generic and specific features of the invention herein described, and all statements of the scope of the invention which as a matter of language might be said to fall therebetween. 100

Having described my invention, what I claim as new and desire to secure by Letters Patent is:

1. An article holder, including an open-ended article-housing receptacle, an article-mounting member movable within said receptacle to project the housed article through the open end thereof, a cover normally closing said receptacle end and movable to a point beyond the opposite end thereof, and means to prevent the movement of said mounting member to project said article until the cover has been moved to a point beyond said opposite end of the receptacle. 110

2. An article holder, including an open-ended article-housing receptacle presenting uninterrupted side walls, an article-mounting member movable within said receptacle to project the housed article beyond the same, a cover normally closing the upper receptacle end, means for normally locking said mounting member against outward movement, and means connecting said locking means with said cover and actuated upon the latter being moved through an arc of substantially 180° to release said locking means, said connecting means subsequently 120 acting to impart thrust exerted against said 125 cover. 130

- cover to said mounting member to move the latter and project the article.
3. An article holder, including an open-ended article-housing receptacle, an article-mounting member slidably disposed therein, a cover for said receptacle, means connecting said cover with said mounting member, means for locking said mounting member against movement, said cover being connected with said locking means whereby, when the former is swung from its receptacle-closing station through an arc of substantially 180°, said locking means will be released to permit a projection of said mounting member.
4. An article holder, including an open-ended article-housing receptacle, an article-mounting member slidably disposed therein, a cover for said receptacle, means connecting said cover with said mounting member, means for locking said mounting member against movement, said cover being connected with said locking means whereby, when the former is swung from its receptacle-closing station through an arc of substantially 180°, said locking means will be released to permit a projection of said mounting member, and means for limiting the movement of said cover.
5. An article holder, including an open-ended receptacle, a mounting member slidably disposed within said receptacle, a cover normally closing the upper end of said receptacle, means connecting said cover with said mounting member whereby said cover may be moved to a position beyond the lower end of said receptacle to project said mounting member, and means preventing a movement of the latter until said cover reaches such latter position.
6. An article holder, including an article-housing receptacle, a cup-shaped mounting member slidably disposed therein, a cover normally closing the upper end of said receptacle, means for retaining said cover against accidental movement, a strip extending from said cover to the base of said member and along the outside of said receptacle, a pivot pin connecting said mounting member with the lower end of said strip, said lower end being bent to extend at an angle to the strip body, and the base of said mounting member providing a stop in cooperation with said lower strip end to limit the movement of said cover.
7. An article holder, including an article-housing receptacle, a cup-shaped mounting member slidably disposed therein, a cover normally closing the upper end of said receptacle, means for retaining said cover against accidental movement and arranged in the path of travel of the mounting member to limit the movement thereof beyond a predetermined position, a strip extending from said cover to the base of said member and along the outside of said receptacle, a pivot pin connecting said mounting member with the lower end of said strip, said lower end being bent to extend at an angle to the strip body, and the base of said mounting member providing a stop in cooperation with said lower strip end to limit the movement of said cover.
8. An article holder, including a receptacle having an open upper end, an article-mounting member slidably disposed therein, a cover for said receptacle, means for mounting said cover to move from a position closing the receptacle end to a position at which it extends beyond the opposite end of said receptacle and is adapted to be moved to impart movement to said mounting member, and means preventing a movement of said mounting member by said cover until said cover reaches said latter position.
9. An article holder, including a receptacle formed with open ends, a cover closing the upper receptacle end, an article holder within the receptacle and closing the lower end thereof, and means connecting said cover with said holder whereby the latter may be shifted within the receptacle and means to prevent said cover from shifting said holder a substantial distance until the cover is moved beneath the lower receptacle end.
10. An article holder, including a receptacle formed with open ends, a cover closing the upper receptacle end, an article holder within the receptacle and closing the lower end thereof, means connecting said cover with said holder whereby the latter may be shifted within the receptacle, and means including a part of said connecting means for normally preventing a substantial shifting movement of said holder by said cover.
11. An article holder, including a tube-shaped open-ended receptacle, an article-mounting member shiftable from one end to the other end of said receptacle and disposed within the same, a cover for one end of the receptacle, an arm having one of its ends attached to said cover, its body extending exteriorly of the receptacle, its opposite end extending angularly around the end edge of the receptacle and being pivotally connected to said article-mounting member to retain the latter adjacent one end of the tube when said cover is in position closing the opposite end thereof, the cover and arm being swung to a position beyond the end of the tube adjacent which the mounting member is normally retained whereby pressure exerted upon the cover will shift the mounting member, and said angular arm portion engaging said mounting member to limit the swinging movement of said arm and cover.
12. An article holder, including a receptacle having open ends and presenting un-

interrupted side walls, a mounting member 5
slidable within said receptacle, the lower end
of the receptacle being inturned to limit
the movement of the mounting member, a
5 cover for the upper end of the receptacle, a
flange depending from said cover and en-
gaging with the exterior face of the recep-
tacle, and an arm secured to said cover and
normally lying adjacent the exterior face
10 of the receptacle, its lower end extending
through the lower open receptacle end and
being secured to said article-mounting mem-
ber whereby said mounting member may be
moved to project an article from said recep-
15 tacle only after said cover has been swung to
a downward position.

13. An article holder, including a recep-
tacle formed with open ends and present-
ing uninterrupted side walls, an article-
20 mounting member movable within said re-
ceptacle, and a portion at the upper end of
the receptacle indented to intersect the
path of travel of the mounting member to
act as a stop for the same, a cover for the
25 upper end of the receptacle, and an arm
connected to said cover and extending
through the lower open receptacle end and
being connected to said mounting member
whereby said mounting member may be
30 moved to project an article from said recep-
tacle only after said cover has been swung
to a downward position.

14. An article holder, including a recep-
tacle formed with open ends and presenting
35 uninterrupted side walls, a cover for the up-
per open end of the receptacle, flanges de-
pending from said cover and engaging the
opposite and exterior faces of the receptacle,
an arm secured to said cover and extending
40 immediately adjacent the side of the recep-
tacle and exteriorly thereof, the lower end
of said arm being bent to extend inwardly
through the lower open receptacle end, an
article-mounting member slidable within
45 said receptacle, the inwardly-extending end
of said arm being secured to said mounting
member whereby said mounting member may
be moved to project an article from said

receptacle only after said cover has been
swung to a downward position, and means 50
for confining the movements of said mount-
ing member.

15. An article holder including an open-
ended article-housing receptacle, an article-
mounting member movable within said re-
ceptacle to project an article through the
open upper end thereof, a cover normally
10 closing the upper end of said receptacle, an
arm extending downwardly from said cover
outside said receptacle, and having an in-
wardly extending lower end adapted to en-
gage said mounting member to permit the up-
ward movement of the same by the cover
after the cover is moved to a position be-
neath said receptacle and to prevent a sub-
stantial upward movement of said mounting
member by the cover until the cover reaches
said position.

16. In a lip stick holder, a tubular body, a
lip stick carrier slidable in the body, a clo-
sure for the top of the body, and means op-
erable through the bottom of the body and
connected to the carrier, and to the closure
for operating the carrier both toward and
away from the bottom of the body. 75

17. In a lip stick holder, a tubular body, a
lip stick carrier slidable in the body, a closure
for the top of the body, and an arm operable
through the bottom of the body and con-
nected to the closure and hingedly connected
80 to the carrier for actuating the latter, said
arm in closed position of the closure being
disposed alongside and exteriorly of the
body.

18. In a lip stick holder, a tubular body, a
lip stick carrier slidable in the body, a clo-
sure for the top of the body, and means op-
erable through the bottom of the body and
connected to the closure and to the carrier
so as to be capable in one position of being
90 disposed in the plane of the body whereby
to operate the carrier by a straight thrust
of the connecting means.

In testimony whereof I affix my signature.

CHARLES N. CORYELL.
